METHOD OF PRODUCING A STOCKING

Joseph K. Cobert, Sherbrooke, Quebec, Canada

Application December 18, 1937, Serial No. 180,561

8 Claims. (CL. 66—62)

This invention relates to stockings and a method of manufacturing the same.

Up to comparatively recent years, the manufacture of full fashioned silk hosiery necessitated 5 two major operative steps requiring two separate and distinct knitting machines of different type. The leg portion of the stocking including the heel was made on one machine known in the art as a "legger." The foot portion was made in 10 another machine known as a "footer." Obvious disadvantages in this method of manufacture have long been recognized. The use of two separate complicated and expensive machines required a large amount of space in addition to the 15 expense involved. Moreover, as is well known, the loop formation in knitting varies greatly with different machines. One machine may make a loop slightly longer or of a slightly different configuration than another machine. Thus, when a 20 foot portion is joined to the leg portion of a stocking, each of which is knit on a different machine, the varying loop formation shows up clearly at the joining line and adversely affects the stocking appearance.

25 Machines have recently come into use which are capable of knitting an entire stocking in one operation. Such machines are, however, very expensive and the complete replacement therewith of the many thousands of highly complicated and 30 expensive machines now in use is for the most part out of the question. Many attempts have been made to provide means for converting such machines into ones capable of producing a stocking in one operation. Up to the present time, 35 such attempts have resulted in complicated expensive, and impractical arrangements of little commercial value.

The formation of the heel portion of the stocking has been the difficult step in the production 40 of hosiery on flat knitting machines since it has not been possible, on machines of the usual type, to complete the shaping of the same during the knitting of the leg and foot portions on one machine without transfer of the stocking blank to another machine.

45 The present invention has for its object the provision of a stocking and a method of knitting the same whereby the stocking blank as a unit including the foot portion is formed in a single 50 major operation on one machine of the usual type without substantial alteration thereto and without transfer of the blank at any time to another machine.

An important feature of the invention is the 55 formation, in a separate operation, of the heel

blanks, the individual heel blanks being joined to the main stocking blank when the leg portion thereof is completed and before the formation of the foot portion. This separate production of the heel blanks and their insertion in the main 5 blank at the point mentioned enables the formation of a complete stocking blank on one machine without transfer from one machine to another.

The invention will be described with reference to the accompanying drawing, which illustrates 10 the various steps in the production of a stocking according to the invention and in which

Figure 1 is a view of a stocking blank representing the first step,

Figure 2 is a view of the stocking blank representing the second step,

Figure 3 is a view of the stocking blank representing the third step,

Figure 4 is a view of the stocking blank representing the fourth step and

Figure 5 is a view of the completed stocking.

The leg portion 1 of the stocking, as shown in Figure 1, is knit on a "legger" machine of usual type and includes the ornamental and reinforced high heel portions 2. This step in the operation 20 is continued to the high heel splicing line 3.

At this point, heel blanks 4 are transferred by topping onto the stocking blank, the line of junction being the high heel splicing lines 3. It will be noted that the heel blank, when positioned on the leg portion, has an outwardly extending tab portion 5. An inner handling tab 6 and an outer handling tab 7 are provided on the heel blank, the tabs being defined by the loose knitted courses 8' and 7', which of course also define the end 30 edges of the heel blank proper.

The small heel blanks 4 may be made on a "footer" machine. It will be apparent that several of these heel blanks may be made at one time and that a multiplicity may be produced in 40 a very short time on a single machine. The size and shape of the blank will of course vary with the size of stocking to be made.

At this point, the carrier on the "legger" machine producing the stocking is widened to the 45 points 8 or the desired foot width which will correspond with the outer edge of the heel blank proper, defined by course 7. The knitting is then continued to form the foot portion 9 which is shaped in the usual manner, as shown in Figure 50 50, and provided with the usual reinforced sole portions 10.

The heel of the stocking is now formed, the leg portion being topped onto the needles of a looping machine along a line 11 which, as shown in Fig- 55

ure 3, is of the same length and closely adjacent to the line of juncture between the heel blank and leg portion. The heel blank is then severed from the leg portion along a line between the 5 topping line and juncture line, as indicated at 12. The topping line 11 is normally about two courses below the juncture line or just sufficient to permit a convenient severing operation between the two lines. The heel blank, which is 10 still joined to the foot portion 9, is then swung around to the position shown in Figure 4 with its left hand end edge, as defined by loose course 6', in registry with the topping line 11 of the leg portion on the looping machine. This left hand edge 15 of the heel blank is then also topped onto the needles of the looping machine, the handling tab 6 removed, and the registered edges looped together. It will be obvious that the width of the heel blank should be substantially equal to the 20 line of juncture between it and the leg portion whereby its end edge will also register to length with the topping line 11. The other half of the heel portion is then formed by topping the leg portion onto the looping machine along the 25 line 11 and proceeding as above outlined.

The stocking is then completed, as illustrated in Figure 5, by folding and forming a seam along the meeting edges, the tab portions 7 on the heel blanks being of course removed.

30 It will be observed that, but for the looped line 12, the stocking is exactly similar to those of usual manufacture. There will, however, be no variation in the knitting loops of the foot and leg portions since such portions are formed on 35 the one machine.

In carrying the method of the invention into effect, the use of the usual "footer" machines is eliminated with the exception of possibly one machine which may be utilized for producing the 40 heel blanks. A large saving in space is thereby effected.

I claim:

1. Method of producing hosiery comprising knitting the leg portion of a stocking blank, 45 joining heel blanks along one edge to the high heel splicing edges of said leg portion, knitting a foot portion directly onto said leg portion, severing the connected edges of the heel blanks from the leg portion and looping other edges of the 50 heel blanks to the high heel splicing edges of the leg portion to form a complete stocking blank.

2. Method of producing hosiery comprising knitting the leg portion of a stocking blank on 55 one machine, knitting individual heel blanks on another machine, joining said heel blanks along one edge to the high heel splicing edges of said leg portion, continuing the knitting of a foot portion directly onto said leg portion on said first machine, topping said high heel splicing 60 edges onto the needles of a looping machine, severing the connected edges of said heel blanks from the high heel splicing edges and looping other edges of said heel blanks to the high heel splicing edges to form a complete stocking blank.

65 3. Method of producing hosiery comprising knitting a leg blank on a knitting machine, trans-

ferring previously knitted heel blanks to said machine for interknitted connection along one edge of each heel blank with said leg blank, continuing the knitting of a foot blank directly onto said leg blank on said machine, severing the leg blank from the heel blanks and connecting the heel blanks along other edges to the leg blank. 5

4. Method of producing hosiery comprising knitting a leg blank on a knitting machine, transferring previously knitted heel blanks to said 10 machine for interknitted connection with said leg blank, continuing the knitting of a foot blank directly onto said leg blank on said machine, and subsequently severing the knitted connection between the heel blanks and leg blank and looping 15 the heel blanks to the high heel splicing edges of the leg blank.

5. Method of producing a complete stocking blank as a unit comprising interknitting previously knitted heel blanks along one edge of 20 each heel blank to a leg and foot blank along the line of juncture between the leg and foot portions thereof and during the knitting of the latter, and subsequently severing the connected edges of the heel blanks from the leg portion and 25 connecting another edge of each heel blank to the leg portion.

6. Method of producing a complete stocking blank as a unit comprising interknitting previously knitted heel blanks along one edge of 30 each heel blank to a leg and foot blank along the high heel splicing line thereof and during the knitting of the leg and foot blank, and subsequently severing the connected edges of the heel blanks from the leg portion of the leg and 35 foot blank and looping other edges of the heel blanks to the high heel splicing edges of the leg portion.

7. Method of producing a complete stocking blank as a unit comprising knitting the leg portion of the blank, interknitting the normal inner edges of previously knitted heel blanks with the end of the leg portion, knitting a foot portion as a continuation of the leg portion, and subsequently severing the knitted connection between the inner edges of the heel blanks and the leg portion and connecting the normal upper edges of the heel blanks to the leg portion. 40 45

8. Method of producing a complete stocking blank as a unit comprising knitting on a knitting machine a leg portion of the blank down to the high heel splicing line thereof, transferring previously knitted heel blanks to said machine for interknitted connection along one edge of each heel blank with the leg portion along the high heel splicing line, knitting the foot portion of the stocking blank as a continuation of the leg portion, topping the stocking blank along the high heel splicing line onto the needles of a looping machine, severing the knitted connection between the heel blanks and high heel splicing line, 50 topping the heel blanks onto the needles of the looping machine, and forming a looped connection between other edges of the heel blanks and the high heel splicing edges of the stocking blank. 55 60 65

JOSEPH K. COBERT.
